UNITED STATES PATENT OFFICE.

GEORGE MUELLER, OF SALT LAKE CITY, UTAH.

SCREEN-BOTTOM BREAD-BAKING TRAY.

1,408,766.

Specification of Letters Patent. Patented Mar. 7, 1922.

Application filed May 28, 1921. Serial No. 473,247.

To all whom it may concern:

Be it known that I, GEORGE MUELLER, a citizen of the United States, residing at Salt Lake City, in the county of Salt Lake and 5 State of Utah, have invented new and useful Improvements in a Screen-Bottom Bread-Baking Tray, of which the following is a specification.

The invention relates to a screen-bottom 10 bread-baking tray.

The object of the present invention is to provide a simple, practical and efficient screen-bottom baking tray designed for use in bakers' ovens for baking rolls, biscuits 15 and the like and equipped with means for enabling the screen material constituting the bottom of the tray to be readily adjusted to counteract sagging and looseness from other causes, and to maintain the screen material 20 taut and in proper condition with relation to the framework of the tray.

Another object of the invention is to provide a screen-bottom bread-baking tray which, after the rolls or the like have been 25 placed on it and properly proofed, is adapted to be readily placed into the oven with the screen resting upon the top of the hearth thereby enabling the rolls to be properly baked.

30 Another object of the invention is to provide a screen-bottom, bread-baking tray adapted to save time and labor and capable of enabling the entire batch of rolls to be handled in placing them in and removing 35 them from the oven and adapted to produce a roll of a better texture as the rolls after being proofed are not handled and the fermentation of the rolls is not disturbed and a much larger roll thus produced.

40 With these and other objects in view the invention consists in the novel construction, combination and arrangement of parts hereinafter fully described, illustrated in the accompanying drawings and pointed out in 45 the claims hereto appended, it being understood that various changes in the form, proportion and minor details of construction, within the scope of the claims, may be resorted to without departing from the spirit 50 or sacrificing any of the advantages of the invention.

In the drawings in which like characters of reference designate corresponding parts in the several figures:

55 Figure 1 is a plan view of a screen-bottom

bread-baking tray constructed in accordance with this invention.

Figure 2 is a longitudinal sectional view of the same on an enlarged scale, parts being broken away. 60

Figure 3 is an enlarged transverse sectional view.

Figure 4 is an enlarged detail plan view of one corner of the frame of the tray.

Figure 5 is an enlarged plan view of a 65 portion of the frame illustrating the construction of the intermediate transverse connecting bars.

Figure 6 is an enlarged plan view of the central portion of the tray illustrating the 70 means for tightening the screen material.

In the accompanying drawings in which is illustrated the preferred embodiment of the invention the screen-bottom bread-baking tray comprises in its construction an 75 oblong frame composed of angle side bars 1 and transverse connecting end and intermediate bars 2, 3 and 4, the intermediate bars 4 serving as spreading or spacing bars and the front and rear end bars 2 and 3 being riveted or otherwise secured to the angle side bars 1. The angle side bars 1 have horizontal inwardly extending webs or flanges and outer vertical webs or flanges, the end bars being arranged upon the terminal portions of the inwardly extending webs or flanges of the angle side bars as shown. The front transverse connecting bar 2 is equipped at its center with an upwardly 80 projecting ring or eye 5 preferably formed integral with an attaching plate 6 which is riveted or otherwise secured to the upper face of the upper transverse bar 2. The central eye 5 is adapted to be engaged by a hook or other implement for facilitating 85 the rapid handling of the tray in placing the same in and removing the tray from an oven. 90

The spacing or spreading bars 4 which are preferably constructed of half-round material having reduced flattened terminals 7 provided with longitudinal slots or bifurcations 8 adapted to receive clamping bolts 9 for securing the intermediate transverse bars to the angle side bars. 100

The screen material 10 which is preferably arranged in separate sheets, extends across the frame and has its marginal side portions fitted against and arranged upon the webs or flanges of the longitudinal side 110

bars and the said side marginal portions of the material are clamped against the vertical flanges of the angle side bars by the means of inner longitudinal clamping bars 5 or members 12 which are secured by bolts 13 or other suitable fastening devices to the upwardly extending webs or flanges of the side bars, the marginal side portions of the screen material being provided with slots 10 14 for the passage of the clamping bolts for permitting an adjustment of the screen material by central transverse adjusting bars or members 15. After the adjustment of the screen material has been effected and the 15 screen material drawn to the desired tension the marginal portions are clamped by tightening the side bolts. The side clamping bars or members are provided with recesses 16 to clear the intermediate transverse bars 4 and 20 with central elongated recesses 17 for the terminal portions 18 of the central adjusting bars or members.

The central adjusting bars or members 15 are preferably composed of angle bars having vertical and horizontal webs or flanges, the vertical webs or flanges being cut away at their terminals at 19 to form the said projecting terminals 18. The adjusting bars 15 are arranged upon the screen material which 25 is clamped against the bars 15 by inner clamping bars 20 secured at intervals to the bars 15 by bolts 21. When the central terminal portions of the sides of the screen material are firmly secured to the adjusting 30 bars 15 the latter are adapted to be drawn together by adjusting bolts 22 which pierce the vertical web portions of the bars 15 and the clamping bars. This will enable the screen material to be tightened to the desired tension to take up any slack or looseness resulting from the sagging of the material or from any other cause.

The terminal portions 23 of the angle side bars are preferably bent upwardly as shown 45 to present inclined lower end faces similar to runners so that the angle side bars which serve as runners in introducing the tray into an oven and in removing the tray therefrom, will not catch upon the bottom of the hearth 50 and interfere with the repeated and convenient handling of the tray.

The central recesses of the clamping bars form guides or ways for slidably interlocking the terminals 18 of the adjusting bars 55 with the frame and the intermediate recesses 16 enable the terminals 7 of the half-round spreading bars to be also interlocked with the frame of the tray.

What is claimed is:

60 1. A tray for bakers' ovens comprising side bars having angularly disposed inclined portions forming runners, cross bars connecting the side bars and a foraminous bottom secured to the side bars.

2. A tray for bakers' ovens comprising 65 angle side bars having inwardly extending wings or flanges and upwardly extending wings or flanges, a foraminous bottom extending across the space between the side bars and arranged upon the horizontal wings 70 or flanges and having marginal portions fitted against the inner faces of the upwardly extending flanges, inner clamping bars or members fitted against the marginal portions of the foraminous bottom and securing the same to the side bars, and cross bars connecting the side bars.

3. A tray for bakers' ovens having inwardly extending wings or flanges and upwardly extending wings or flanges, a foraminous bottom extending across the space between the side bars and arranged upon the horizontal wings or flanges and having marginal portions fitted against the inner faces of the angle side bars, inner clamping bars 80 securing the marginal portions of the foraminous bottom to the angle side bars, said side bars having inclined upwardly extending terminal portions forming runners, and cross bars connecting the angle side bars. 90

4. A tray for bakers' ovens comprising angle side bars having inwardly extending wings or flanges, a foraminous bottom extending across the space between the side bars and arranged upon the inwardly extending wings or flanges, clamping bars or members securing the marginal portions of the foraminous bottom to the angle side bars, said side bars having inclined terminal portions, intermediate cross bars spacing the side bars 100 and secured to the same and end connecting bars secured to the inclined portions of the side bars, one of the end bars being provided with a central projecting eye or ring.

5. A tray for bakers' ovens comprising 105 angle side bars having inwardly and forwardly extending webs or flanges transverse connecting end bars, a foraminous bottom arranged upon the angle side bars, transverse spacing or sliding bars extending 110 across the space between the side bars and secured to the same and clamping bars mounted on the angle side bars and securing the marginal portions of the foraminous bottom to the said side bars and provided at 115 the spacing or sliding bars with recesses.

6. A tray for bakers' ovens comprising side bars, a foraminous bottom composed of separate adjustable sheets having their marginal portions secured to the side bars and transverse adjusting bars provided with means for clamping the said sheets and having their terminals slidably interlocking with the side bars and adjusting means connecting the said adjusting bars for stretching the sheets. 120

7. A tray comprising angle side bars, end bars connecting the side bars, a foraminous

bottom consisting of sheets of screen material having their marginal portions arranged on the angle side bars, clamping bars mounted on the side bars and securing 5 the said sheets to the side bars and provided with opposite recesses forming guides, transverse adjusting bars having their terminal portions slidably mounted in the guides, means carried by the adjusting bars for 10 clamping the said sheets and adjusting means for connecting the adjusting bars for placing the sheets under tension.

8. A tray comprising a frame having angle side bars, a foraminous bottom consisting of sheets of screen material, clamping bars mounted on the side bars and securing the marginal portions of the sheets to the frame, said clamping bars being provided with intermediate and central recesses, intermediate transverse sliding bars secured to the angle side bars and having their terminals fitted in the said intermediate recesses whereby they are interlocked with the frame, central adjusting bars connected with the said sheets and having their terminals slidably interlocking with the central recesses and adjusting screws connecting the adjusting bars for placing the sheets under tension.

30 9. A tray comprising a frame having angle side bars, a foraminous bottom con-

sisting of sheets of screen material having their side marginal portions arranged on the angle side bars and provided with slots, clamping bars securing the said marginal 35 portions of the sheets to the side bars and having fastening means passing through the said slots, said clamping bars being provided with intermediate and central recesses in their lower edges, intermediate 40 sliding bars secured to the angle side bars and having terminal portions fitted in the intermediate recesses, angle adjusting bars having projecting terminals arranged in the central recesses of the clamping bars, means 45 carried by the angle adjusting bars for engaging the said sheets and means for adjustably connecting the adjusting bars for placing the sheets under tension.

10. A tray comprising an oblong frame 50 having angle side bars, a foraminous bottom, clamping bars securing the foraminous bottom to the side bars of the frame, spreader bars substantially half-round in cross-section and having flattened terminals provided with slots and fastening devices arranged in slots and securing the spreading bars to the angle side bars.

In witness whereof I hereunto affix my signature.

GEORGE MUELLER.
